UNITED STATES PATENT OFFICE.

JAMES PRIESTNALL NAYLOR, OF DULWICH, LONDON, ENGLAND.

APPARATUS FOR DISPLAYING ADVERTISEMENTS, SIGNALING, AND THE LIKE.

1,213,528.

specification of Letters Patent.

Patented Jan. 23, 1917.

Original application filed August 2, 1911, Serial No. 642,030. Patent No. 1,191,023, dated July 11, 1916.

Divided and this application filed September 15, 1913. Serial No. 789,930.

To all whom it may concern:

Be it known that I, JAMES PRIESTNALL NAYLOR, a subject of the King of England, residing at Dulwich, London, in England, 5 have invented a certain new and useful Improvement in Apparatus for Displaying Advertisements, Signaling, and the like, of which the following is a specification.

This invention relates to controlling mechanism for operating groups of electrically actuated elements being more particularly applicable to those operated by two or more magnetic functions as described in my Patent No. 1,191,023, granted July 11, 1916, of 15 which this application is a division.

The combination of the controller as herein described together with the elements and monograms as described in the specification referred to enables apparatus to be constructed 20 usable for displaying advertisements, signaling or communicating messages by day or night, wherein letters or characters are caused to appear upon a background by the selection and operation of the proper elements from a group of elements upon a support or background, a series of said monogrammatic formations or groups of elements hereinafter termed "monograms" being suitably juxtaposed so that words or sentences 25 of the required length can be caused to appear and disappear upon the background.

One type of element described in the prior specification consists of a white screen for daylight display, a black shutter or flap arranged 30 to cover such daylight screen, and a lamp to cause illumination of the daylight screen when displaying in darkness so that when a group of such elements are provided with a black support by operation of 35 the black shutters the white screens can be disclosed or covered thus causing them to appear and disappear by day, and when the individual lamps are illuminated by night or in darkness, the daylight screens are 40 thereby rendered visible or defined. The operation of bringing the shutters into the display position and the non-display position may be effected by two magnetic devices, the momentary excitation of one of 45 which causes the display, and the momentary excitation of the other causes the non-display, and to elements of this type the controller described hereinafter is more par-

ticularly applicable, although it will be obvious that such a controller may be utilized 55 for elements for daylight only, that is, elements without a self-contained lamp, and for elements for night display only, that is, for similar magnetic mechanism operating the lamp contact only.

The object of my invention is to provide improved controlling apparatus for operating groups of elements as described herein, the said controlling apparatus to be capable of being operated manually by means of 65 a keyboard, and automatically by means of a perforated record strip.

With the above object in view, my invention consists in the combination and arrangement of the parts as will hereinafter 70 be fully described and claimed.

The annexed drawings illustrate an example of construction of my invention, in which:

Figure 1 is a diagram illustrating the arrangement of the composing keys and means by which they coöperate with the monogram selector and indicator; Fig. 2 is a further diagram illustrating the electrical connections between the elements, composing keys, 75 illuminating circuit, clearing circuit and monogram selector; Fig. 2^a is a detail of the contact stud and conductive elements; Fig. 3 illustrates the general arrangement of the apparatus; Fig. 4 is a detail of Fig. 2; Fig. 5 is a view of one of the monogrammatic units; 80 and Fig. 6 is a view of means for moving and rewinding the strip, which is used for automatically controlling the contact keys.

In my prior application above noted I 90 have described various forms of elements adapted to be operated so that their visual members may be brought into the display position by the momentary passage of an electric current and again to be operated for 95 bringing them into the non-display position by the momentary passage of another electric current. The arrangement of the electro-magnetic mechanism of one of such elements is illustrated for convenience in Fig. 100 2, the lamp display member only being shown.

B is a lever capable of rotating upon the pivot P and it is caused to travel in a direction remote from the catch G by means of 105 the tension of the spring S. It is normally

retained in the position shown by the catch G engaging with the pin F so that when the catch is lifted the arm B will travel toward the lamp by the tension of the spring 5 S thus establishing electrical contact between the member C^{2A} which is insulated from the arm B and the two contacts C⁰: when this mechanism is utilized to operate daylight members they are actuated by suitable 10 mechanical connections to the member B and they will then display or cease to display in unison with the opening and closing of the lamp contacts C⁰, C^{2A}.

When it is desired to clear the sign, that 15 is bring all daylight members into the non-display position or extinguish all lamps, the coil C is energized by momentarily connecting the conductors C¹, C³ with the source of electricity when the magnet C is then energized and will attract the armature CA 20 which is attached to the member B causing it to travel toward the said magnet. In doing this the spring S is brought under tension, the catch G is raised sufficiently to 25 allow the pin F to be retained thereby, and the contacts C⁰ C^{2A} are opened. The energization of the coils C may then be discontinued, and the mechanism will remain in the position shown in the drawing, as the 30 catch G prevents the spring S from imparting motion to the member B. When it is desired to cause display, the conductors D¹, D² are connected with the source of electricity thus energizing the coil D which will draw 35 up the catch G out of engagement with the pin F thus allowing the spring S to draw the member B so that the contacts C⁰ C^{2A} are established. After the catch G has released the pin F the coil D may be deenergized 40 and the element will remain displayed until the coil C is again energized. It will be obvious however, that when the lamp L is illuminated it will consume current during the period of display, or while contact is 45 established between C⁰ and C^{2A}.

A plurality of monograms, one of which is substantially shown in Fig. 5, each composed of a sufficient number of elements is indicated by M¹⁰ M²⁰, Fig. 2, and when such 50 groups form a sign or signaling device they can be operated by controlling mechanism (as described herein) capable of: (a) manual operation by means of a single keyboard, (b) automatic operation by means of a perforated strip or the like, (c) determining the time and duration of the display of the message or character. It is not necessary that controlling apparatus for operating the sign shall comprise the whole of the above 55 features as for example, a controller comprising the features (a) and (b) only may be employed or either of these two features alone may be employed.

Fig. 1 illustrates the composing keys and 60 their mode of actuation whereby they are

caused to coöperate with the monogram selector.

The composing keyboard consists of an insulating support or base K¹ upon which are mounted contact bars K² preferably of equal number to the elements comprised upon one monogram of a plurality of similar monograms, each bar being connected by conductors 1 to 6 to the display coil of each of the corresponding elements throughout a plurality of monograms, and such connection being normally open until the monogram selector causes such coils to be connected to the circuit in the manner described and illustrated in reference to Fig. 2, enabling the group of elements upon any one monogram to be electrically connected to a single composing keyboard in a manner already known to those skilled in the art.

Mounted above the contact bars and connected to a pole of the electrical circuit opposite to that of the display coils are the composing key bars K³ each of which is furnished with projecting contacts K⁴ in electrical connection therewith and for the purpose of energizing the group of contact bars K² such groups corresponding with the number of elements upon each monogram. The disposition of the contacts K⁴ determines the number and the disposition of the contacts K² to be energized by the bar K³ and thereby enabling groups of elements corresponding with the disposition of the contacts K⁴ to be energized upon the face of the sign when the bar K³ is actuated into the contacting position.

The bar K³ is attached to a stem K⁵ which passes through guide plates K⁶, K⁷, supported by the member K⁸. Upon such stem is affixed an iron concentric projection or armature core K⁹ and below such projection is located a spring K¹⁰ which rests upon the supporting guide K⁷, and such spring is of sufficient strength to maintain the bar K³ out of contact as shown in the drawing.

A magnetic coil K¹² will when energized by connecting conductors K¹²⁰ and K¹²¹ with a source of electricity, act upon the iron core K⁹ thus causing operation of the key by means alternative to manual pressure upon K¹³ and the object of which is described in connection with Fig. 2. The key-board is also provided with a member K¹⁴ which engages with all keys and is capable of being moved against the pressure of the spring K¹⁵ by means of the projection K¹⁶ carried upon the key stem K⁵ so that when the finger-key K¹³ is depressed, the inclined surface of K¹⁶ operating against the aperture K¹⁷ causes the member K¹⁴ to travel toward the spring K¹⁵ and bringing the said spring under compression, so that when the key K¹³ is released the member K¹⁴ is returned into its normal position shown. All the keys upon the keyboard being arranged to operate

the member K¹⁴ in the manner described the said member carrying the pawl K¹⁸ which is arranged to engage with the wheel K¹⁹ so that when any finger-key is depressed, the said pawl due to its attachment with the member K¹⁴ is advanced to engage a ratchet tooth of the wheel K¹⁹ and when this finger-key is released the spring K¹⁵ causes the return of the sliding member K¹⁴ and the pawl K¹⁸ thus causing the required partial rotation of the ratchet wheel K¹⁹. Mounted fast upon the same spindle K³⁰ as the wheel K¹⁹ and rotated thereby, is the pinion S¹ which actuates the monogram selector which I will now describe.

The automatic selection of the monograms is accomplished by the manipulation of the keyboard by means of that part of the mechanism illustrated in the upper section of the Fig. 1. It consists of a fixed insulating drum S² carrying the six contacts S³, and the contacts S⁴, the contacts S³ being arranged in the same relative position as the monograms forming the sign (and in the example it is assumed that there are six monograms arranged in two rows of three). Each of the contacts S³ is connected by the conductors M¹ to M⁶ to the monogram circuits so that when they are energized they cause the setting coils of a group of elements in the same relative position upon the sign to be connected to the group of conductors part of which are numbered 1 to 6. A concentric internal carrier S⁵ is supported by the spindle S⁶ attached to the traveling carriage S⁷ which slides in the bearings S⁸, S⁹, and the carrier S⁵ in addition to the lateral motion which it acquires through its supporting carriage is also rotatable upon the spindle S⁶ in such manner that a point upon the carrier S⁵ may be successively brought into a position coinciding with the various contact studs S³, S⁴. Upon the concentric carrier S⁵ is mounted a contact stud S¹⁰ fed by the conductive strip S¹¹ which is connected to a source opposite to that feeding the coils actuating the multicontact switches which connect the display coils to the conductors 1 to 6 as shown in Fig. 2 and herein-after described so that as the contact stud S¹⁰ may be both rotated and moved laterally it may successively establish electrical contact with the studs S³, S⁴, thus causing the setting coils of the elements comprised within the monograms to be successively connected to the contact bars K² of the keyboard as determined by the motion of the said carrier.

I have already described how the wheel K¹⁹ is rotated and that its rotation is transmitted to the pinion S¹. By reference to the drawing it will be seen that this pinion engages with the rack S¹² which is attached to the frame S⁷ so that as the said pinion is rotated step by step the frame S⁷ and conse-

quently the drum S⁵ acquire the same lateral motion and consequently the frame S⁷. Drum S⁵ continuously rotates in one direction and if desired the contact studs S³, S⁴ may be repeated to fill the periphery of said drum. The gearing of the rack S¹² and the pinion S¹ being so proportioned as to permit the contact S¹⁰ to travel through an interval equal to the distance between the centers of the contact studs S³, a "click" S¹³ being provided to correctly lock the carrier in its position until the pinion S¹ is forced around another step

Upon the outside of the drum S² and in the position of the contacts S³ may be placed markings to indicate the relative positions of the various monograms upon the sign, and a pointer S¹⁴ attached to the drum S⁵ with its point coinciding with the center of the stud S¹⁰ will then always indicate upon the external drum S² the position of the next monogram which will be operated when a key is pressed or alternatively when the end of the line has been reached. As the motion of the monogram selecting stud S¹⁰ takes place after the release of the key K¹³ it will be seen that the motion takes place after the contacts K², K⁴ are opened, thus connecting the next monogram in readiness for operation by the next key depressed, and step by step it successively connects the monograms until the last monogram of one of the horizontal rows has been connected when it is then necessary to lift the pawl K¹⁸ and draw the carrier to the left and rotate the drum S⁵ so that the contact S¹⁰ contacts with the first stud of the next line, this is electrically accomplished in the following manner:—On release of the key K¹³ contact is established between the contact S⁴ and the stud S¹⁰ causing current to flow from the + source to conductors S¹⁵ to bar S¹¹ and stud S¹⁰ to top stud S⁴ to conductor S¹⁶ and S¹⁷ to the magnetic coil S²² to conductor S¹⁹ and thus to the opposite pole of the source, causing the coil S²² to be energized and exert traction upon the armature S²⁴. Current also flows from the conductor S¹⁶ and S¹⁸ to the coil S²³ through conductor S²⁰ to the bridged contacts S²⁵ to the conductor S²¹ and thus to conductor S³⁵ leading to the opposite pole of the source thus causing the armature attached to the pawl lever K¹⁸ to be drawn toward it lifting the pawl out of contact with the wheel K¹⁹ and also causing the contact K²⁶ to enter the mercury cup K²⁷ when the operating current will have a path alternative to that already described through the + conductors, mercury cup K²⁷ and contact K²⁶ to the flexible bridge wire S²⁸ to the conductor S¹⁸ so that the conductor S¹⁷ feeding the two magnetic coils S²³, S²² is then connected to the + conductor at the contact S¹⁰, S⁴, and the mercury cup K²⁶ K²⁷

with the pawl raised out of mesh from the wheel K^{19} . The coil S^{22} exercising tractive force on its armature S^{24} causing the carriage S^7 to be drawn toward it and consequently interrupting the contacts S^4 with S^{18} but owing to the alternative path through the mercury cup contact being maintained it enables the coil S^{22} to continue to draw the carrier S^7 and consequently the concentric rack S^{30} toward the pawl S^{29} with which it is constructed to engage, and the continuing motion will further cause the pawl pivoted at S^{31} to engage with the rack and the continuing lateral motion of the carriage will cause the carrier S^5 to be rotated through an angle equal to the distance between the rows of studs, S^3 , the motion continuing until the said pawl assumes a position indicated by its dotted outline and in contact with the device S^{25} which connects together the two conductors S^{20} , S^{21} which it causes to open so the remaining path K^{27} , K^{26} , S^{28} , S^3 , S^{20} , S^{25} , S^{21} and S^{35} is interrupted deenergizing the magnet coil S^{23} allowing the pawl to assume its position of engagement with the wheel K^{19} and consequent interruption of the mercury cup contact and deenergization of the magnetic device S^{22} . All parts concerned have now been returned to normal. The step by step selective operation previously described will then continue till the end of the next line when it will be seen that the contact stud S^{10} in addition to establishing contact on one of the contact studs S^4 causing the previously described cycle of operations to be performed also establishes contact upon the stud S^{32} , thus permitting current to flow from the + source through conductive strip S^{11} through contact stud S^{10} conductor S^{33} to the magnetic coil of the electric switch C^{34} and thus through the conductor S^{35} to the - pole of the source causing the switch C^{36} to close a subsidiary circuit communicating with the clearing coils of the elements upon the sign so as to effect the clearing or non-display of the said elements. The said switch C^{36} engages the conductors S^{33} , S^{35} and consequently the coil C^{19} (Fig. 3) thus causing the compound contact-maker or gang-key C^{20} to operate the group of clearing devices including relays C^{11} to C^{16} .

With a sign of sufficient lines of monograms the action described would be equal to one revolution of the contact drum S^5 so that the sign would be cleared and be ready to receive actuation of the group of elements upon the first monogram of the first line as soon as the keyboard is manipulated.

When there are insufficient lines of monograms to permit disposition around the periphery of the drum they may as above described be geometrically repeated and each stud in a position relative to the monograms

would be connected together so that after partial revolution of the selector drum the sign is cleared and the controller keyboard is again placed in relation with the first monogram in the first line. The action of the clearing circuit is described in connection with Fig. 2. It will also be obvious that if the sign consisted of one row of monograms that the rotation of the contact S^{10} would be unnecessary.

Fig. 2 illustrates in detail the internal connections of the elements which have already been described to connections to the control conductors, the method by which the setting coils are successively placed in relation with the composing keyboard, the method by which the clearing devices are operated and the means adapted for utilizing a perforated paper strip to vary the connections of the circuit so as to manipulate the whole functions of the sign without the said paper strip device having to break an electric current of sufficient strength to generate a destructive arc.

The group of elements E^1 , E^2 , E^3 represent an equipment of the monogram M^{10} and the group of elements E^4 , E^5 , E^6 , represent a group of elements on monogram M^{20} .

I will now proceed to describe the action of the controller when operated by means of a perforated strip as shown by Fig. 2.

A metallic bar B^8 connected to a positive pole of a source of electricity is located under the brushes B^1 , B^2 , B^3 , etc., and such brushes are maintained out of contact with the said bar by means of a paper strip PP or other convenient arrangement producing equivalent results. Means are also provided whereby the paper strip may be traveled under the contact brushes as by winding upon a roller, and the brushes which it is desired to cause to contact with the said bar are permitted so to do by the provision of holes in the paper as P^1 , P^2 , P^3 allowing the desired sequence of contacts to be made as the paper is wound upon a containing spool, and allowing successive combinations and sequences of brushes to make and interrupt electrical connection with the bar B^8 .

A preferred form of means for moving and rewinding the perforated paper strip PP , is shown in Fig. 6 in which a perforated paper strip PP , moves forward over contact bar B^8 , under contact brushes B^1 to B^2 . The strip PP is wound from roller 237 and upon roller 237' and any suitable means (not shown) may be used to rewind the same. The action of the contact fingers upon the bar B^8 through the perforations P^1 and so forth, is such as to cause the excitation of the proper electro-magnets under the keys, said electro-magnets being connected to the proper contact fingers in the same order and sequence as the perforations upon

- the record and in the same way as if the keys were being manually operated. Contact fingers 39 and 39^a are provided so that when the end of a record is reached, a perforation travels under the contact 39 and operates the reversing switch 240, causing the motor 241 to rewind the record and at the same time disconnect the monogram circuit so that the elements are not operated upon 5
- 10 during the rewinding process. When the commencement of a record is reached, a perforation passes under the contact 39^a, thus causing the reversing switch 240 to operate again, causing the record to move in a normal direction with the monogram circuit reconnected and the elements operating. Now if for example it is desired to operate elements E¹ and E² upon monogram M¹⁰ perforations would be provided in the paper strip in the positions P¹, P² so that simultaneously the brushes B¹ and B⁵ establish contact with the source by contacting the bar B⁸. Current will then flow through the following circuits from the source through 20
- 25 the contact bar B⁸ under the paper strip through perforation P¹ to the brush B¹, through the conductor M^{1A} to the magnetic coil SR¹ and to the negative pole of the source.
- 30 Excitation of the coil SR¹ will cause the switch SR³ to establish contact with the pins SR⁴¹. A subsidiary circuit is then established from the positive pole of the source to the contact SR³ through SR³ to the conductor SR⁴ to the magnetic coil MC¹ and thus to the negative pole of the source. Excitation of the coil MC¹ causes attraction of the armature MC²¹ and consequent operation of the insulating rod MC³ causing the contacts MC⁴, MC⁵, MC⁶ to contact with the pairs of terminals MC⁷, MC⁸, and MC⁹, thus placing all the display coils on the monogram M¹ in electrical connection with the conductors 1, 2 and 3. The brush B⁵ makes simultaneous 40
- 45 contact through the perforation P² with the + conductor of a source so that current will then flow through the brush B⁵, conductor B⁵⁰, coil K¹² connected therewith and to the opposite pole of the same source thus causing the armature K⁹ to be drawn up and establish the following subsidiary circuit, from the positive conductor of a source to keyboard bar 4 through contact K² engaging therewith to the stem K³ of the key and thus to the contacts K² which engage with the bars connected with the conductors 1 and 2, current will then flow from a positive source to bar 4 through the stem K³ of a key K⁹ through the contacts K² engaging with the bars connecting conductors 1 and 2 through the conductors 1 and 2 to the contacts MC⁷ and MC⁸ which are bridged by the switches MC⁴ and MC⁵ and thus through the conductor D¹ in element E¹ through the coil D to the conductor D² and thus to the opposite 50
- 55 pole of a source, an exactly similar contact being established in the element E². In the manner previously described the two elements are then displayed. Due to the motion of the paper strip contact with the brush B⁵ is broken and the whole of the circuits just described as being made are then opened but the elements will remain displaying until the clearing coils C are energized. This is accomplished by the perforation P³ being 70
- 75 brought under brush B⁷ when a circuit is established from the positive pole of the source through the perforation P³ to the brush B⁷, conductor C⁶, coil C¹¹ to the negative pole of a source. This causes the armature C⁷ to contact with C⁸ from which it is normally kept out of contact by the spring C⁹. A subsidiary circuit is then established from the positive pole of a source through the armature C⁷ to the contact C⁸ to the conductor C¹ thence to coil C of element E¹ to the conductor C³ and thus to the opposite pole of a source, simultaneous excitation of similar coils in elements E² and E³ taking place. In the manner already described the 80
- 85 armature CA is operated thus causing the elements to assume their non-display position, both elements E¹ and E², and as the element E³ has not been displayed its coil C is excited, but no motion of the display element takes place due to the fact that it is already in the position to which it would be drawn had its condition been otherwise. The motion of the paper P² having interrupted contact between the brushes B⁷ and the positive pole of the source the magnetic apparatus just enumerated assumes its normal open circuit position and the elements upon monogram M¹⁰ remain cleared or in the non-display position without any further current 90
- 95 being consumed, and when it is desired that other combinations upon other monograms shall be actuated, different combinations of the devices described may be operated in the method described to produce the desired results. It will therefore be understood that if the paper PP is traveled at a constant rate of speed that the perforations P¹ P² may be caused to establish their contacts at a given time of day and that the space intervening 100
- 105 between P¹ P² and P³ will determine the time during which the elements will remain displayed, and it will be understood by those skilled in the art that additional brushes and perforations may be provided whereby the 110
- 115 mechanism utilized for operating the paper strip may be controlled and that by such means it may be caused to stop at a given time or to re-roll, in such case means would be provided to disconnect the whole of the sign operating mechanism from its source in order to prevent erratic operation which would otherwise result due to passing the paper perforations backward under the brushes B¹ to B⁷.

The manner in which the automatic selector described by Fig. 1 coöperates with the system of conductors shown by Fig. 2 is indicated again showing the conductive strips S^{11} , the stud S^{10} , two of the contacts S^s , two of the conductors M^{1A} and M^{2A} leading therefrom, and the conductor S^{15} leading from the source of the contact strip S^{11} . When it is desired to operate automatic selection from the keyboard it is necessary that the brushes B^1 to B^7 are insulated or disconnected from the contact bar B^s and this may be done by introducing an unperforated section of paper between them and the contact bar. Operation of the keyboard will then cause simultaneous selection of monogrammic groups of elements together with the actuation of combinations of the said groups, clearing being then effected by manual manipulation of the clearing keys, and in order that such manipulation shall be convenient for practical purposes I should construct my apparatus as illustrated by Fig. 3.

Fig. 3 illustrates the arrangement of a keyboard for practical working, but for the sake of clearness I have omitted the automatic contacting device operated by a paper strip or equivalent which I have clearly shown in Fig. 2, in connection with which figure I have already described the action of the contact maker S^{10} and S^s and shown the mode of connecting the relays SR^2 and SR^3 . I have also described the action of the clearing relays C^{11} to C^{16} , and the method by which the keys K^o energize groups of the composing conductors 1, 2 and 3, and the method whereby the coils K^{12} are energized from the automatic contact device.

The present figure shows the means whereby I may alternatively clear or bring to the non-display position the elements upon individual monograms or collectively by the depression or operation of one of the individual clearing relays C^{11} to C^{16} , causing current to flow from the + source to the bar C^{32} through the hinge C^{33} to the movable conductive section of the relay C^7 and thus to the clearing coil C of the sign elements.

When it is desired that the whole of the sign shall be cleared the conductors S^{33} and S^{35} are energized in the manner shown in Fig. 1, thus energizing the coil C^{19} and causing the gang key C^{20} to contact with the corresponding gang of studs C^{21} which are connected by the conductors C^{22} to the group of conductors C^s and the coils of the clearing relays are then energized by a circuit that is established from a positive source to the hinge C^{23} and thus to the contacting device C^{20} , contact C^{21} , conductor C^{22} , the coils of the relays C^{11} to C^{16} and to the bar C^{32} and thus to the opposite pole of the source. The contacting devices on the relays are normally held in the non-contacting

position by the spring C^o as illustrated in Fig. 2. The selective relays are of similar construction and are similar in their mode of operation, but as it is seldom desirable to cause the same letter to appear upon every monogram of the sign, no means of collectively operating the keys are provided as with the clearing circuit.

The keys K^o , and relays C^{11} to C^{16} , and SR^1 to SR^6 in addition to making the contacts already described may each be provided with an additional contacting device such as R^s connected by a conductor R^2 to the terminal R^1 so that when such terminals are connected to suitable time or character recording devices the manipulation of the key will not only cause the performance of operating functions of the sign, but will also cause such functions to be recorded. The key K^{oA} is a space key whose sole function is to operate the ratchet gear shown in Fig. 1 without making a group of contacts upon the bars K^2 and for the sole object of causing the automatic monogram selector stud S^{10} to pass over a contact S^s communicating with a monogram which it is desired to leave vacant of displayed elements.

By an inspection of the diagram it will be clear that any of the composing relays may be operated by the excitation of their individual magnetic devices and in the manner already described and shown in reference to Fig. 2, it will also be obvious that the keys controlling these three functions may be manually manipulated so that if for example when using the automatic selector (in the manner described in connection with Fig. 1) an error were made in one letter the said letter may be deleted by operating the clearing key and the monogram so cleared may be placed in relation with the keyboard by the operation of the correct selective key while manually operating the correct composing key by this means (as for correction purposes) may be substituted upon any one of the monograms, and it will also be obvious that by hand manipulation of the three groups of keys shown, letters may be displayed and cleared in any desired manner or sequence either letter by letter, row by row, line by line, or erratically, and it will be seen that when electric lamps are used for the purpose of visualizing the elements the individual contacts within the elements may be made and broken independently of the energization of the circuit feeding such lamps as when elements are utilized with daylight flaps for displaying in the daylight, the illuminant then being unnecessary, or alternatively the lighting switch may be actuated after the closing of the lamp contacts and before the opening of the lamp contacts individual to the elements so as to preserve such contacts from damage which might result from arcing.

What I claim as my invention and desire to secure by Letters Patent of the United States is:—

1. In an advertisement and signal display device, the combination of a plurality of similar monogrammic groups of elements, each element individually capable of operation to display and non-display position by energization of a plurality of electro-magnetic devices, three systems of contact keys, circuit connections between the keys and the monogrammic groups, one system of said keys being for selection of a monogrammic group, a second system including composing keys for selection of elements on the particular monogrammic group, and a third system for deletion of displayed elements by operating those elements only which have been displayed, and manipulative means for controlling the said three systems of keys.

2. In an advertisement and signal display device, the combination of a plurality of similar monogrammic groups of elements, three systems of contact keys, circuit connections between the keys and the monogrammic groups, one system of said keys being for the selection of the monogrammic group, the second system formed of composing keys for selection of elements upon the particular monogrammic group, and a third system being for the deletion of displayed elements, and automatically operative means for controlling the said three systems of keys, said automatic means including a control strip having only as many contact devices as there are systems of keys.

3. In an advertisement and signal display device, the combination of a plurality of similar monogrammic groups of elements, three systems of contact keys, circuit connections between the keys and the monogrammic groups, one system of said keys being for the selection of the monogrammic group, another system comprising composing keys for selection of elements upon the particular monogrammic group, and the third system being for the deletion of displayed elements, manually operative means for controlling the said three systems of keys and automatically operative means for controlling the said three systems of keys,

said automatically operative means being constructed and arranged for alternative manual operation.

4. In an advertisement and signal display device, the combination of a plurality of similar monogrammic groups of elements, three systems of contact keys, circuit connections between the keys and the monogrammic groups, one system of said keys being for the selection of the monogrammic group, another system including groups of keys for selection of elements upon the particular monogrammic group, and a third system being for the deletion of displayed elements, and automatically operative means for controlling the said three systems of keys, said automatic means including a control device having only as many contacts as there are systems of keys, the duration of the display of the selected elements being determinable by the distance between the contacts and the speed of the control device.

5. In an advertisement and signal display device, the combination of a plurality of similar monogrammic groups of elements, each element individually capable of operation to display and non-display position by the energization of a plurality of electro-magnetic devices, three systems of contact keys, circuit connections between the keys and the monogrammic groups, one system of said keys being for selection of a monogrammic group, a second system including composing keys for the selection of elements on the particular monogrammic group, and a third system for the deletion of displayed elements by operating those elements only which have been displayed, manipulative means for the said three systems of keys and automatically operative means for controlling the said three systems of keys, said automatic means including a control strip having contact devices corresponding in number to the systems of keys.

In witness whereof I have signed this specification in the presence of two witnesses.

JAMES PRIESTNALL NAYLOR.
